LIGHT SENSITIVE APPARATUS

William Francis Tedham, London, England, assignor to Electric and Musical Industries Limited, Hayes, England, a company of Great Britain

Application October 27, 1933, Serial No. 695,381
In Great Britain November 11, 1932

5 Claims. (Cl. 250—27.5)

The present invention relates to light sensitive apparatus and more particularly to photo-electric devices.

In order to increase the magnitude of the photo-current developed when light of a given intensity impinges upon the light sensitive surface of a photo-electric device, it has been proposed to provide a photo-electric device of the type comprising a secondary cathode adapted to emit secondary electrons when electrons from the light sensitive surface or primary cathode impinge thereon.

In photo-electric devices of this type, the primary and secondary cathodes have been constituted hitherto by plane, rectangular electrodes disposed parallel or inclined at an angle to one another with a plane anode of mesh material disposed symmetrically between them.

When oxidizing the surfaces of parallel plate electrodes, difficulty has been experienced in obtaining a uniform discharge in oxygen, at the usual pressures of 0.5 to 1 mm. of mercury, as the edge effects are serious. This lack of uniformity is increased when the plates are inclined to one another and it has been found impossible to produce cathodes of high sensitivity when the surfaces thereof have been unevenly oxidized.

A further difficulty is that the process of cathode formation following the introduction of the light sensitive material such as caesium, cannot readily be observed when the electrodes are disposed in the above described known manner. Hence the amplification produced by secondary emission in this known type of photo-electric device is virtually nullified by the low efficiency of the cathode which can be employed.

According to the present invention, there is provided a photo-electric device comprising a primary cathode adapted to emit electrons when subjected to illumination, a secondary cathode adapted to emit secondary electrons when electrons from the primary cathode impinge thereon, and an anode disposed between said primary and secondary cathodes, wherein said primary or secondary cathode or both are of curved or dished shape, the concave side or sides being directed towards the anode.

Preferably the anode is in the form of a straight wire or cylinder and the cathodes are arranged concentrically or co-axially with respect to the anode and upon opposite sides thereof.

A preferred embodiment of the invention will now be described by way of example, reference being made to the accompanying drawing, in which

Fig. 1 is an illustration of a photo-electric device constructed in accordance with the present invention, and

Fig. 2 is a plan view of the electrodes of the device illustrated in Fig. 1.

Like parts in the two figures bear the same reference numbers.

Referring now to the two figures, a photo-electric device comprises an evacuated glass envelope 1 having disposed within, a primary cathode 2, a secondary cathode 3 and an anode 4. Each electrode is mounted in usual manner, upon an independent support which is sealed through a pinch 5 in a re-entrant stem of the envelope 1.

The primary cathode 2 comprises a hollow semi-cylinder, preferably of silver, the concave side of which is directed towards the anode 4, the latter being constituted by a rigid filament located along the central longitudinal axis of the primary cathode 2.

The secondary cathode 3, which also comprises a hollow semi-cylinder of silver, is disposed on the side of the anode 4 remote from the primary cathode 2 and is arranged co-axially therewith. The diameter of the secondary cathode 3 is considerably less than that of the primary cathode 2. It may conveniently be about one-quarter that of the primary cathode 2.

In one tube constructed in accordance with the invention, the anode and secondary cathode are maintained at potentials of about 400 and 300 volts respectively relative to the primary cathode.

If desired, the primary and secondary cathodes may be in the form of concentric hemispherical shells and the anode may then be in the form of a small ball held at the center of the shells. A central horizontal section of such an arrangement would then be as shown in Fig. 2.

Whichever arrangement of electrodes is adopted the concave surfaces of the two cathodes are sensitized by oxidation and subsequent deposition of caesium or other suitable material. Oxidation may be effected in known manner by introducing oxygen into the envelope 1 of the device to a pressure of 0.5 to 1 mm. of mercury and passing a high voltage, high frequency or direct current discharge between the anode 4 and cathodes 2 and 3. If either or both of the cathodes is part-spherical in shape, it has been found preferable to employ a high frequency discharge. With part-cylindrical cathodes, a direct current discharge has been found to produce the better result. A layer of caesium is then deposited upon the oxidized surfaces of the cathode 55

by any known or suitable process of evaporation and condensation.

The envelope 1 may be rendered opaque except for a part 6 facing the concave side of the primary cathode 2, and this part is left transparent and constitutes the window of the device through which light may pass, in the direction indicated by the arrows, to the primary cathode 2.

In operation, when light falls upon the primary cathode 2, electrons are emitted and, under the influence of the electrostatic field, maintained between the electrodes, some of these electrons pass to and are collected by the anode 4 while others travel on to the secondary cathode 3 and there cause an increased number of secondary electrons to be emitted. These secondary electrons travel to the anode 4 and augment the total number of electrons impinging thereon.

With the electrodes arranged as described above, uniform oxidation of the cathodes is possible and, in addition, formation of the light sensitive surface may be readily observed and the incident light is not impeded to any great extent by the secondary cathode.

25 The cathodes need not be of accurately hemispherical or semi-cylindrical form but may be of any dished shape similar to those described above.

Having now particularly described and ascertained the nature of my said invention, and in what manner the same is to be performed, I declare that what I claim is:

1. A photo-electric device comprising a primary cathode adapted to emit electrons when subjected to illumination, a secondary cathode adapted to emit secondary electrons when electrons from the primary cathode impinge thereon, and an anode disposed between said primary and secondary cathodes, both of said cathodes being

curved and mounted with their concave sides directed toward each other and towards the anode.

2. A photo-electric device as claimed in claim 1, wherein the anode is in the form of a thin rod, and the primary and secondary cathodes are in the form of hollow semicylinders.

3. A light sensitive device comprising a primary cathode adapted to emit electrons when subjected to illumination, a secondary cathode adapted to emit secondary electrons when electrons from the primary cathode impinge thereon, and an anode disposed between said primary and secondary cathodes, said cathodes being disposed concentrically with respect to said anode. 15

4. A light sensitive device comprising a semi-cylindrical primary cathode adapted to emit electrons when subjected to illumination, a semi-cylindrical secondary cathode having its concave side facing the concave side of the primary cathode adapted to emit secondary electrons when electrons from the primary cathode impinge thereon, and an anode disposed between said primary and secondary cathodes, said cathodes being mounted coaxially with respect to one another. 20

5. A light sensitive device comprising a semi-cylindrical primary cathode adapted to emit electrons when subjected to illumination, a semi-cylindrical secondary cathode adapted to emit secondary electrons when electrons from the primary cathode impinge thereon, and an anode disposed between said primary and secondary cathodes, the diameter of the cylinder in which the surface of said primary cathode lies being 30 greater than the diameter of the cylinder in which the surface of said secondary cathode lies. 35

WILLIAM FRANCIS TEDHAM.
